(57) **CLAIM**

The ornamental design for a hand-held network test device, as shown and described.

DESCRIPTION

FIG. 1 is a bottom, front, and right side perspective view of a hand-held network test device;

FIG. 2 is a bottom, rear, and left side perspective view of the hand-held network test device of FIG. 1;

FIG. 3 is a left side view of the hand-held network test device of FIG. 1;

FIG. 4 is a right side view of the hand-held network test device of FIG. 1;

FIG. 5 is a front plan view of the hand-held network test device of FIG. 1;

FIG. 6 is a rear plan view of the hand-held network test device of FIG. 1; and,

FIG. 7 is a bottom plan view of the hand-held network test device of FIG. 1.

Surface shading is included to show the character and contour of the surfaces of three dimensional aspects of the design. The features illustrated in evenly-spaced dashed lines are included for the purpose of illustrating environmental structure and form no part of the claimed design.
